UNITED STATES PATENT OFFICE.

CHARLES GOETZ, OF MOUNT SAVAGE, AND WILLIAM A. HUSTON, OF FROSTBURG, MARYLAND.

CAR-BRAKE.

SPECIFICATION forming part of Letters Patent No. 624,787, dated May 9, 1899.

Application filed October 20, 1898. Serial No. 694,128. (No model.)

To all whom it may concern:

Be it known that we, CHARLES GOETZ, of Mount Savage, and WILLIAM A. HUSTON, of Frostburg, Allegany county, Maryland, have 5 invented certain new and useful Improvements in Car-Brakes, of which the following is a complete specification, reference being had to the accompanying drawings.

The object of our invention is to produce a 10 simple and effective device for preventing injury to brakemen consequent upon the parting of brake-chains.

In railway-cars, particularly freight-cars, equipped with hand-brakes it frequently happens 15 that a brake-chain parts under excessive strain—as, for example, upon heavy grades—while the brakeman is at the wheel. In applying the brakes it becomes necessary for an operative to exert himself and throw his 20 weight upon the wheel in order to produce the requisite tension upon the brake-chain. If during this operation the chain part, the sudden and abrupt interruption of the counter strain upon the brake-shaft causes the 25 shaft to whirl in obedience to the power applied by the brakeman and to hurl him from the car. The result in most cases is that the brakeman either loses his life or is severely injured. It is to automatically prevent the 30 whirling of the brake-shaft under conditions above described that our invention is designed.

In the accompanying drawings, Figure I is a 35 bottom plan view of one portion of a freight car equipped with our device. Fig. II is a perspective end view of the same with the truck omitted and showing the brakeman's platform partially broken away to illustrate the usual arrangement of the brake-shaft, 40 ratchet, and pawl.

Referring to the figures on the drawings, 1 indicates a car-body, and 2 the end frame-pieces thereof.

3 indicates a brake-shaft which is free to 45 move within suitable vertically-aligned bearings in the frame-pieces 2 and in the brakeman's platform 4. The shaft 3 is, as usual, provided at its upper end with a hand-wheel 5 and above the platform with a ratchet 6, with 50 which engages a pawl 7 upon the platform. Underneath the frame-pieces 2 is secured at

one end to the shaft a brake-chain 8, that is secured at the other end (see Fig. I) to a brake-lever 9, operatively pivoted, as indicated at 10, to a brake-beam 11 and connected, as by a rod 12 and lever 13, to the truck-frame 14.

The above-described mechanism is illustrated as an example of a type of brake mechanism in ordinary use. This particular mechanism is shown only as a means of illustrating the principle of our invention, which is applicable to any form of brake mechanism that includes a rotatory brake-shaft.

The elements of our invention, as illustrated, comprehend a ratchet 15, secured to the shaft 3, preferably underneath the frame-pieces 2. The ratchet 15 is similar to the ratchet 6, except that their teeth are oppositely operative.

In operative proximity to the ratchet 15 we provide a dog 16, pivoted, as indicated at 17, to the bottom of the frame-pieces 2, preferably against a plate 18, secured thereto. The pivotal movement of the dog in one direction is limited by a pin 19, projecting from the plate 18. The dog is held normally out of engagement with the ratchet 15, as by a coiled spring 20, secured at one end, as indicated at 21, to the tail of the dog and at 22, to a suitably-fixed support on the bottom frame of the car-body. A chain 23 is secured at one end, as indicated at 24, to the dog, near its toothed end, and at its other extremity, as indicated 25, to a member actuated by the brake-beam—for example, the lever 9.

We prefer to employ a yielding section 26 in the chain 23, consisting, for example, of a coiled spring, in order to relieve any sudden 30 strain upon the chain 23 that otherwise might suffice to break it.

The operation of our device is as follows: Assume that a brakeman or other operative in applying the brakes is rotating the shaft 3 by aid of the wheel 5. If while the brakeman is operating the wheel 5 the chain 8 should part, the brake-beam 11, relieved from the strain upon it, will rebound suddenly and with force, causing the end of the lever 9 to 35 which the chain 8 was attached to retreat in a direction opposite from that in which it was

drawn under the tension of the chain 8. Thereupon the chain 23 is caused to actuate the dog 16 against the force of its spring 20, and it causes the teeth of the dog to engage 5 with the teeth of the ratchet 15. In practice, the parting of the chain 8 and the actuation of the dog through the chain 23 must occur simultaneously or substantially so. Consequently the wheel 5 instead of tending, 10 through the whirling motion which would be imparted to it as ordinarily constructed, remains stationary, its tendency to rotation occasioned by the parting of the chain 8 being promptly resisted by the engagement of 15 the teeth of the dog 16 with the teeth of the ratchet 15.

What we claim is—

1. The combination with a car, brake-shaft, chain, and beam, of automatic means for interrupting the rotation of the shaft dependent for its operation upon the parting of the chain, substantially as set forth.

2. The combination with a car, brake-shaft, chain, and beam, of a dog in operative proximity to the shaft, and adapted, when in engagement therewith, to interrupt its rotation,

means for holding the dog normally out of engagement with the shaft, and mechanism connecting the dog to the beam, whereby, upon parting of the brake-chain, the dog is 30 forced into engagement with the shaft to interrupt its operation, substantially as set forth.

3. The combination with a car, brake-shaft, chain and beam, of a ratchet secured to the 35 shaft, a spring-controlled toothed dog in operative proximity to the ratchet, and a connection between the dog and the brake-beam, substantially as set forth.

4. The combination with a car, brake-shaft, 40 chain and beam, of a ratchet secured to the shaft, a spring-controlled toothed dog in operative proximity to the ratchet, and a yielding connection between the dog and the brake-beam, substantially as set forth.

In testimony of all which we have hereunto subscribed our names.

CHARLES GOETZ.

WILLIAM A. HUSTON.
